UNITED STATES PATENT OFFICE

157,326

COMBINATION BUMPER GUARD AND FOG LIGHT

William B. R. Bell, Dallas, Tex.

Application January 18, 1949, Serial No. 287

Term of patent 3½ years

(Cl. D14—6)

To all whom it may concern:

Be it known that I, William B. R. Bell, a citizen of the United States of America, residing at Dallas, in the county of Dallas and State of Texas, have invented a new, original, and ornamental Design for Combination Bumper Guard and Fog Light, of which the following is a specification, reference being had to the accompanying drawings, forming part thereof.

Figure 1 is a front elevational view of a combination bumper guard and fog light, showing my new design.

Fig. 2 is a plan view.

Fig. 3 is a rear elevational view.

Fig. 4 is a side view of a combination bumper guard and fog light.

Fig. 5 is a sectional view taken on line 5—5 of Fig. 3.

I claim:

The ornamental design for a combination bumper guard and fog light, as shown.

WILLIAM B. R. BELL.
